7 Claims. (Cl. 60—41)

The present invention relates to the operation of explosion chambers of the constant volume type into which explosive charges of fuel and air are periodically charged and periodically ignited, 5 the explosion gases being discharged intermittently in puffs after each explosion for use outside the chamber, for example, in an explosion gas turbine.

It is an object of the present invention to provide an improved method of charging and discharging an explosion chamber of this type, whereby the capacity of the explosion chamber as compared with that of known chambers of the same general class is greatly increased. It has 10 already been proposed by me (see my United States application, Ser. No. 297,799), to dispense with the use of separate charges of scavenging air by employing the combustion-supporting air itself to effect discharge of the residual combustion gases. The present invention contemplates an increase in the economy of operation of an explosion chamber of the kind indicated by charging the fuel simultaneously with the combustion supporting air into the combustion chamber while 20 at the same time preignition of the charge is eliminated by causing certain conditions of flow.

In the manner of operation referred to, the air destined to support the next explosion in an explosion chamber is charged in such a manner, 30 that it assumes the form of a piston and, the exhaust member of the chamber being open, drives before it the residual gases of the previous explosion without penetrating, or being penetrated by, such gases to any appreciable extent. To accomplish this result, the combustion air must enter the chamber when the residual gases have been expanded to somewhat below the pressure of this air and such pressure must be sufficiently greater than that of the exhaust 40 pressure beyond the chamber to effect the displacement of such gases within the necessarily short interval of time apportioned to this phase of the working cycle; but the difference in pressure of the residual gases and the incoming air 45 must not be so high that it expands and diffuses so rapidly through the chamber that whirls and eddies are created which prevent such air from assuming the form of a continuous piston-like mass.

50 In the new method according to the invention, the charging of the fuel is accomplished in the following manner. Shortly after the opening of the air inlet member, the fuel inlet member is opened and caused to discharge fuel into the 55 chamber, preferably along a path similar to that

traversed by the air. By such timing of the fuel and air inlet members, I provide a body of pure air between the receding body of hot residual gases and the incoming fuel (which mixes with the air simultaneously charged therewith), so that 60 the fuel is protected against pre-ignition by such gases, while at the same time uniform distribution of the fuel in the chamber is promoted by the fact that the fuel is admitted during almost the whole of the air charging period and while the 65 nozzle valve is open, permitting rapid flow and thorough penetration and diffusion of the fuel through the chamber.

I have found that in the practice of my invention, best results are secured by the use of an 70 elongated cylindrical explosion chamber having fuel and air inlets located at one end of the chamber and a conical section between the air inlet member and the cylindrical walls of the chamber. Explosion chambers of this construction have 75 the peculiarity that the spreading of introduced air over the width of the chamber is promoted by the diffusor action of such conical section, so that when the conditions of pressure referred to above are observed, the air assumes the form of a piston 80 in its movement through the chamber. Through the avoidance of whirling accomplished in this manner there is formed a comparatively planar dividing wall between the entering air and the residual gases in the explosion chamber, the 85 timing of the opening and closing of the members controlling the residual gas outlet and the fresh air inlet being so controlled that the dividing wall can be stopped at any desired point of the explosion chamber by closing the exhaust valve at 90 the proper instant.

My invention is based upon the experience that the combustion of a mixture is more complete the more homogeneously the mixture fills the explosion space, and accomplishes such homogeneous filling of the chamber in the manner outlined above. The teaching of the prior art has been to the effect that the closure element, i. e. the exhaust or nozzle valve, of the explosion chamber should be closed comparatively early, and in any 95 case before opening of the fuel inlet valve, because it was considered otherwise possible, due to the irregular distribution of the air entering the explosion chamber with respect to the residual gases of the previous explosion in the methods of control heretofore employed, for the fuel particles to become ignited upon contact with such residual gases and thus produce an ineffective, premature explosion if the closure element was still open. The closing of the closure element before open- 100 105 110

ing the fuel inlet member did indeed avoid this danger with more or less certainty, but it did not promote the filling of the explosion chamber with a homogeneous mixture, because the necessary pressure drop for effecting penetration by the fuel of the body of air in advance of the closure element was lacking.

According to the present invention, the closing of the closure or exhaust member in the types of explosion chambers indicated above takes place while the air and fuel inlet valves are open, only after such member has been actually or approximately reached by the dividing wall between the residual combustion gases of the previous explosion and the piston-like body of charging air which displaces the same. It has already been suggested to open again the exhaust member of the explosion chamber after the fuel inlet valve has been opened, but the carrying out of this mode of operation required the arrangement of special control devices at the exhaust member, so that this procedure found no practical use. It has also been already proposed to hold the exhaust or nozzle valve open also at the beginning of the fuel admission; but this proposal was expressly characterized as disadvantageous, because there was no possibility, due to the irregular penetration of the charging air by the residual explosion gases, of avoiding dangerous pre-ignition. It was also not possible to close the exhaust member of the explosion chamber after it had actually or nearly been reached by the dividing wall between the residual gases and the charging air because with the known modes of procedure such an extensive penetration of the explosion chamber by a homogeneous combustible mixture would have led to pre-ignition. In my improved method of operating explosion chambers, preferably as applied to an elongated cylindrical explosion chamber provided with fuel and air inlet valves at one end of the chamber and also a conical section between the air inlet member and the cylindrical walls of the chamber, these difficulties are eliminated, because it becomes possible to prevent the meeting of fuel or fuel-air particles with the residual combustion gases. If the air inlet valve is first opened, and only thereafter is the fuel inlet valve opened, so that the hot residual combustion gases are directly contacted and displaced by pure air only, the fuel valve being opened a definite time interval after the air valve, there arises a zone of pure air between the residual gases and the mixture of fuel and air, such pure air, because of its piston-like formation, precluding any possibility of a meeting between the hot residual gases and the fuel-air mixture. As the inflowing charging air drives the fuel-air mixture toward the residual gases even when the exhaust member of the explosion chamber has already been closed, the air inlet member is advantageously closed before the fuel air mixture has reached the residual gases. In this case the source of ignition is located within the reach of the homogeneous mixture which completely fills the chamber so that rapid and certain ignition of the mixture and its complete combustion are assured by this procedure. The admission of fuel can thereby be made to continue after the closing of the air inlet member and can be stopped when the ignition of the mixture in the chamber begins. In this way there are assured, in addition to certain ignition, the complete combustion of the charge and the maximum charging of the explosion chamber.

75 On the accompanying drawings are schemati-

cally represented the various steps of my new process in a constant volume explosion chamber. In said drawings,

Fig. 1 shows the conditions in the explosion chamber when the air and fuel inlet valves and the exhaust valve are open, the dividing zone between the residual gases and the intermediate protecting cushion of pure air being in advance of the igniting means; 80

Fig. 2 shows the closing of the exhaust valve when the said dividing zone has almost reached the same; 85

Fig. 3 indicates the closing of the air valve as the fuel-air mixture penetrates or diffuses into the intermediate cushion of pure air, the fuel valve still being open, as indicated by the arrow; 90

Fig. 4 illustrates the progress of the explosion following ignition, all the valves being closed; and

Fig. 5 is a view illustrating a suitable form of controlling mechanism for the explosion chamber. 95

In all of the figures, the numeral 1 indicates an elongated explosion chamber the main portion of which is cylindrical. At one end of the chamber are located the fuel inlet member 2 and the air inlet member 3. The fuel inlet member 2 may be of any suitable construction, and in the form illustrated is constructed as a nozzle having one or more discharge openings, and may be provided in known manner with a check valve to prevent the flow of combustion gases into the fuel conduit 2a. As the specific construction of the fuel charging member forms no part of the present invention, the same has not been illustrated in detail. The air inlet member 3 is connected with the cylindrical portion of the explosion chamber by means of a conical intermediate member 4. A closure or exhaust member 5 is arranged opposite to the fuel and air inlet members 2, 3, the said exhaust member closing the conical neck 7 of the explosion chamber in advance of the nozzle 6; for this reason the closure member will be referred to as a nozzle valve in the subsequent description of my invention. An igniting element 8 in the form of a spark plug is arranged in the neck portion 7 of the chamber. 110

According to the present invention, the method of operating an explosion chamber of the type illustrated for obtaining certain ignition, complete combustion, and maximum filling or charge without increasing the duration of the working cycle, is conducted as follows: 125

The nozzle valve still being open following the discharge of the products of combustion, the air valve 3 is opened and shortly thereafter the fuel valve 2. The charging air (shown as dotted stippling) passing through the conical connecting section 4 takes the form of a piston and at 135 the instant represented in Fig. 1 has nearly completely displaced the residual combustion gases (shown as curved line stippling) of the previous explosion through the open nozzle valve 5. Because of the piston-like displacement of the residual gases by the incoming air, there is formed a rather sharply defined dividing zone or wall between the residual gases and the zone of pure charging air which was formed by the opening of the air valve in advance of the fuel valve. The dividing zone or wall between the residual gases and the piston-like body of air is indicated at 140 9-9. The dash lines in the figures indicate the advance of the fuel through the chamber. 145

Fig. 2 shows the conditions in the combustion

150

chamber at the instant in which the dividing zone or wall 9—9 between the residual gases and the pure charging air has almost reached the nozzle valve. At this instant the nozzle valve

5 is closed. A small amount of gases is trapped, so as, among other reasons, to provide security against the loss of the costly charging air. In this position of the dividing zone 9—9, nearly the whole of the chamber is filled with a homogeneous mixture of fuel and air, so that further opening of the nozzle valve would be without purpose and would only be accompanied by the danger of loss of charging air from the chamber. Only the zone of pure air and also the small 10 amount of trapped gases, if any, are at this instant free of fuel. According to the invention, therefore, the admission of fuel and also the admission of air is continued until the condition indicated in Fig. 3 is reached.

20 Fig. 3 shows the condition in the chamber when the fuel-air mixture begins to diffuse toward and penetrate the residual gases, so that at this instant the danger of pre-ignition appears. In order to avoid this danger, the air inlet valve is closed 25 and the movement of the fuel-air mixture thereby greatly reduced, the igniting element being already within the reach of the homogeneous mixture of fuel and air filling the chamber without the direct contact between the residual gases 30 and the mixture having occurred. The fuel valve is nevertheless still open so that the chamber can be filled with a mixture of highest combustibility; at the same time the charging of the chamber with the maximum quantity of fuel and 35 air mixture is made possible.

Fig. 4 shows the conclusion of the fuel admission and the advance of the explosion flame following the ignition of the mixture in the chamber, as indicated by the concentric arcs. The 40 combustion thus still possesses the character of an explosion, the latter not being disturbed by the continuance of the fuel feed.

Fig. 5 shows an arrangement to control the working parts of the explosion chamber and 45 give them the proper timing. 10 represents the fuel pump, which supplies the fuel to the fuel inlet member 2. The air inlet member 3 and the exhaust member 5 are operated by pistons 11, which are actuated by means of oil supplied from 50 the revolving controller 14. The exhaust or nozzle valve 5 is provided with a piston similar to the piston 11 associated with the air valve 3, at suitably timed instants determined by the construction of the revolving controller 14, pres-

55 sure oil is charged by the conduit 5a against the piston of the valve 5 to effect opening thereof. It will be understood that the piston on the valve 5 is so arranged that the pressure fluid fed by conduit 5a acts against the lower surface

60 thereof so as to effect opening of the valve, as distinguished from the construction of valve 3 wherein the pressure fluid acts against the upper, or rather outer, surface of the piston 11. The revolving controller 14 is filled with a liquid, such 65 as oil, under pressure which it receives through a conduit 14a from a pump (not shown), an air chamber 14b being provided to equalize the pressure of the liquid. As the revolver 14 is rotated by the gearing 15 driven by a motor 16, the 70 conduits 5a and 11a of each explosion chamber are are brought into temporary communication at the proper instants with the interior of the controller through grooves 14c in the circumference of said controller which communicate with the interior 75 thereof through ports 14d. For a more

complete description of the operation of the controller, reference is had to my United States Patents Nos. 877,194 and 1,763,154.

The words "elongated cylindrical explosion chamber" of the above specification are intended to include all kinds of explosion chambers which, due to their shape, provide the possibility for the incoming air to assume the form of a piston and to drive before it the residual gases of the previous explosion without penetrating, or being penetrated by, such gases to any appreciable extent. Instead of a straight cylindrical form, there may, for instance be employed a slightly conical or spherical form of combustion chamber or any other suitable form of elongated chamber.

The most efficient working of the new method will be secured when the pressure of the combustion supporting air is sufficient to produce the highest velocity of the discharging residual gases so as to shorten the phase of scavenging and 95 charging the combustion chamber. This velocity is known as the critical velocity and a definite minimum ratio of air pressure to exhaust pressure is required to attain this velocity.

I claim:

1. The improvement in the art of operating an elongate, substantially cylindrical, constant volume explosion chamber having a conical inlet section and a controllable air inlet and fuel inlet at the charging end and a controllable outlet 105 at the opposite discharge end thereof, comprising exploding an explosive mixture of fuel and air confined within said chamber, opening such outlet to effect discharge of the high temperature, high pressure explosion gases before they have 110 done external work, opening said air inlet and charging air into such chamber at such pressure that the air assumes the form of a piston and drives the residual gases before it, opening the fuel inlet and introducing fuel into said chamber 115 shortly after the opening of said air inlet and before the air has penetrated far into the chamber, the air inlet and the outlet remaining open, so that a relatively narrow body of pure air intervenes between the retreating residual gases 120 and the incoming fuel and air mixture and fuel enters the chamber as the residual gases are being expelled by the advancing body of pure air, closing the outlet when the dividing zone between the residual gases and the body of pure air has 125 approximately reached the same, closing the air and fuel inlets, and igniting the air and fuel mixture.

2. The method according to claim 1, wherein the fuel inlet is closed upon ignition of the fuel- 130 air mixture.

3. The method as set forth in claim 1, wherein the air inlet is closed before the fuel-air mixture has reached the residual gases.

4. The method as set forth in claim 1, wherein 135 the air inlet is closed before the fuel inlet.

5. A pistonless, constant volume explosion chamber suitable for use in explosion turbines and having an elongate, substantially cylindrical body portion and a conical inlet section; air 140 and fuel inlet members at the inlet end and an exhaust member at the outlet end of said chamber opposite such inlet end; an igniting element; and controlling mechanism operative upon said members and constructed to open first the ex- 145 haust member following an explosion in the chamber, then the air inlet member, and shortly thereafter, when the air has penetrated only partially into the chamber, the fuel inlet member, while maintaining the air inlet member and the 150

exhaust member open, so that the air assumes the form of a piston aided by the configuration of the said inlet section of the chamber and drives the residual gases before it, a relatively narrow body of pure air intervening between the retreating residual gases and the incoming fuel, said mechanism operative to close said exhaust member when the latter has been approximately reached by the dividing zone between the residual gases and said body of pure air, and subsequently to close the air and fuel inlet members.

6. A pistonless, constant volume explosion chamber suitable for use in explosion turbines and having an elongate, substantially cylindrical body portion and a conical inlet section; air and fuel inlet members at the inlet end and an exhaust member at the outlet end of said chamber opposite such inlet end; and controlling mechanism operative upon said members and constructed to open first the exhaust member following an explosion in the chamber, then the air inlet

member and shortly thereafter, when the air has penetrated only partially into the chamber, the fuel inlet member, while maintaining the air inlet member and the exhaust member open so that the air assumes the form of a piston aided by the configuration of the said inlet section of the chamber and drives the residual gases before it, a relatively narrow body of pure air intervening between the retreating residual gases and the incoming fuel, said mechanism operative to close said exhaust member when the latter has been approximately reached by the dividing zone between the residual gases and said body of pure air, and to close the air inlet member in advance of the fuel inlet member.

7. A combustion chamber as set forth in claim 5 wherein the outlet section of the chamber is of reduced size, the igniting element being located in the said reduced outlet section.
